UNITED STATES PATENT OFFICE.

FRED B. MANLEY, OF PATERSON, NEW JERSEY, ASSIGNEE TO TEXTILES DEVELOPMENT CORPORATION, OF NEW YORK, N. Y., A CORPORATION OF DELAWARE.

FABRIC.

Application filed October 17, 1922. Serial No. 595,142.

To all whom it may concern:

Be it known that I, FRED B. MANLEY, a citizen of the United States, residing at Paterson, in the county of Passaic and State 5 of New Jersey, have invented certain new and useful Improvements in Fabrics, of which the following is a specification.

My present invention relates to a fabric particularly adapted for use in belting. In 10 the production of such belting, the fabric is coated with rubber or similar compound and a number of layers combined together. In such a belting, the warp threads should be as nearly inextensible as possible, because 15 substantially the only strain on the belt is longitudinally thereof. On the other hand, since such belts are at times turned over small pulleys, the belt should be capable of bending crosswise of these warp strands 20 rather easily, while, in order that the belt shall have lateral stiffness, the resistance to bending parallel to the warp strands should be comparatively great. When the 25 fabric is used for belting, it should also be of such a character that belt hooks may be inserted in the belt to fasten the ends thereof together without danger of pulling out of the fabric.

The novel fabric described herein has all 30 of the foregoing qualities, and in addition, is of such a character that the rubber coating may be applied thereto, so as to be substantially locked to the surface of the fabric in the direction in which such rubber is 35 liable to be pulled when the fabric is used in belting.

Fig. 1 is a plan view of an illustrative form of my novel fabric.

Fig. 2 is a cross section on the line 2—2 40 of Fig. 1.

Fig. 3 is a cross section on the line 3—3 of Fig. 1.

For purposes of illustration, I have shown an embodiment of my invention particularly 45 adapted for use in belting, in which the cord or yarn warp strands 10, preferably in the form of inextensible cords having but little stretch, are located side by side without intervening space between adjacent 50 cords. These cords extend in straight, parallel lines throughout the length of the fabric, being without undulations either in the plane of the fabric or at right angles thereto.

The weft or filler strands 11 extend across 55 the cord strands 10 on either side thereof,

the weft strands being relatively widely spaced apart. Such weft strands extend across the warp substantially without undulations.

Preferably between each pair of warp 60 strands 10, there is a binder strand 12 which passes alternately over the weft strands 11 on opposite sides of the warp 10, these binder strands preferably being of relatively 65 small diameter and exerting enough pressure on the weft strands 11 to hold these latter and the cord strands 10 in position in the fabric, but without drawing the weft strands 11 down between the cord strands 10.

When the fabric so far described is used 70 in belting, the fabric is coated with rubber or other composition in the usual manner, and then several plies are pressed together, with the cords 10 running lengthwise of the belt. When the belt is subjected to longitudinal 75 pull in use, such pull will cause a longitudinal extension of the belt only by the amount of the elasticity of the cord strands 10 themselves. Since these strands lie in straight lines in the fabric, there will 80 be no stretching of the belt due to the straightening out of undulations in the cords.

When the fabric is used for belting, I prefer to proportion the diameters of the 85 weft strands 11 and their relative spacing along the cord strands 10, so that, while there will be sufficient space between these weft strands to permit the composition to pass between them down to the surfaces of the cord strands 10, nevertheless the weft 90 strands will present sufficient resistance to bending crosswise of the fabric (i. e., parallel with the cord strands 10), so that the belt will be much stiffer crosswise than it is lengthwise. This will produce a belt 95 which will turn around small pulleys, and at the same time, will have sufficient lateral stiffness to maintain itself flat in passing from one pulley to another.

With the fabric which I have described, 100 it will be understood that the resistance to bending does not depend merely on the sum of the resistance to bending of all of the individual weft strands. When the fabric is bent crosswise of the weft strands 105 11, such bending is resisted not only by the strands themselves, but also by the binder strands 12, because by such bending, the weft strands on the outside of the bend tend to be elongated 110

small size between adjacent cords for interlocking the filler strands and serving to maintain the cord warps and filler strands in position.

5. A woven belt fabric having straight filler strands, relatively inextensible cord warps in close contact and free of undulations for carrying the load, and binder strands of relatively small size for interlocking the straight filler strands free of undulations to the cord warps.

10. 5. A hose and belting duck comprising a plurality of primary warp ends in close relation and in rigid contact throughout their 15 length, a plurality of filling threads spaced from each other upon opposite sides of the warp ends, and secondary warp ends of relatively small size for tying the filling ends to the warp ends, the filling ends forming 20 spaced ribs upon opposite sides of the rigidly bound primary warp ends and disposed transversely of and in protective relation with said warp ends, said ribs on one side of the sheet of the warp ends being in staggered relation with the ribs on the other side of said sheet.

25. 6. A hose and belting duck comprising primary warp ends parallel with each other in the same plane and laid in close contact 30 each with the adjacent ends throughout their length to form a solid sheet, spaced filling threads located upon one side of the

said sheet and extending at a right angle to the primary warp ends, a second set of spaced filling threads located upon the opposite side of the solid sheet from the first said filling threads and arranged in staggered relation thereto, that is to say with the spaces of one set of filling threads alternating with those of the other set, and secondary warp ends of relatively small diameter interlocking with and binding the spaced filling threads to the solid sheet of primary warp ends all substantially as described whereby is produced a duck where- 40 in the constituent parts are in intimate relation and free of interstices or spaces between the adjacent parts.

7. A hose and belting duck comprising a plurality of primary warp ends laid in close contact throughout their length to form a solid sheet, a plurality of spaced filling threads located in staggered relation upon opposite sides of the sheet, and secondary warp ends of relatively small size 50 interlocked with the alternate filling threads, said filling threads forming ribs raised above the surface of the solid sheet of primary warp ends and in protective relation thereto.

Signed at Baltimore, Maryland this 13th day of October, 1922.

FRED B. MANLEY.
